Primary Examiner — Caron D Veynar*Assistant Examiner* — Abraham Bahta(74) *Attorney, Agent, or Firm* — Renner, Otto, Boisselle & Sklar, LLP(57) **CLAIM**

The ornamental design for a food container, as shown and described.

DESCRIPTION

The FIGURE is a front view of a food container showing our design, side and end views being substantially a line.

The broken lines shown herein are for illustrative purposes only and form no part of the claimed design.

The stippling shown herein indicates securing of a first side of the food container to a second side of the food container.

1 Claim, 1 Drawing Sheet(56)
